Des. 185,718
Patented July 21, 1959

185,718

PORTABLE CARRIAGE FOR COMPRESSORS OR THE LIKE

Roy C. Patton, Charlotte, N.C.

Application March 24, 1958, Serial No. 50,141

Term of patent 14 years

(Cl. D14—3)

Figure 1 is a perspective view of the portable carriage for compressors or the like showing the flanged wheels in elevated position embodying my new design; and

Figure 2 is a side elevational view of the portable carriage for compressors or the like looking at the opposite side from that shown in Figure 1 and showing the flanged wheels in lowered position.

I claim:

The ornamental design for a portable carriage for compressors or the like, substantially as shown.
